UNITED STATES PATENT OFFICE.

LEWIS L. SWEET AND MIKE MORLEY, OF WALLACE, IDAHO.

BALL MILL.

Application filed December 7, 1922. Serial No. 605,519.

To all whom it may concern:

Be it known that we, LEWIS L. SWEET and MIKE MORLEY, citizens of the United States, residing at Wallace, in the city of Shoshone 5 and State of Idaho, have invented new and useful Improvements in Ball Mills, of which the following is a specification.

This invention relates to apparatus for grinding ore and other material, and more 10 particularly to grinding mills of the ball-and-drum type.

It is the object of the present invention to provide a grinding mill of the kind stated embodying certain novel and 15 proved features of construction and modes of operation to be hereinafter described and claimed, and in order that the same may be better understood, reference is had to the accompanying drawings, wherein,—

20 Figure 1 is an elevation of the mill;

Fig. 2 is a vertical section on the line 2—2 of Fig. 1;

Fig. 3 is a central longitudinal section, and

25 Fig. 4 is an elevation of a liner plate.

Referring specifically to the drawings, the rotary drum is composed of two end sections or heads 5, connected on the inside by an annular series of liner plates 6, which latter 30 therefore form the side of the drum. To the heads are also connected, on the outside thereof, cylindrical plates 7 which extend inwardly toward each other, but only partly across the drum, so that they are spaced at 35 their inner ends, and there is left in the side and intermediate the ends of the drum, an opening 8 which is spanned by the plates 6 and extends completely around the drum circumferentially to form an outlet for the 40 ground or crushed material. To the inner edges of the plates 7 are secured angle irons

9. The liner plates 6 are provided with perforations or apertures 10 to permit passage of the crushed material to the side outlet 8 of the drum. The drum heads 5 have hollow trunnions 11 through which the material to be ground is fed into the drum.

Referring to Fig. 2 it will be noted that the liner plates 6 are assembled and secured in overlapping relation at their adjacent 50 ends. By means of bolts 12 passing through the overlapping ends of the liner plates and through the drum ends 5, the latter are rigidly connected. The bolts 12 also pass through the plates 7 for securing the same to the drum ends. Adjacent plates 6 are also

bolted together intermediate their ends, as shown at 13. The overlapping arrangement of the plates 6 produces a stepped surface in the interior of the drum, the steps or 60 shoulders running in the direction of the length of the drum. This arrangement of the plates materially assists the grinding action.

Intermediate its ends, at the site of the 65 outlet 8, the drum is surrounded by a stationary cylindrical casing 14 having angle irons 15 secured to its ends. At the bottom, this casing has a discharge opening 16, and beneath the latter is located a tank 17 into 70 which the crushed material is discharged. The casing 14 is provided with suitable supports 18, and the drum is eccentrically located in the casing so that the drum is closest to the casing at the top thereof, as shown 75 in Fig. 2.

In operation, the material to be ground or crushed is fed into the drum through the hollow trunnions 11 at the ends thereof. The crushed particles pass through the perforations 10 in the liner plates 6 and through the side opening 8 of the drum into the housing 14, which latter guides them to the opening 16 for discharge into the tank or other receptacle 17. The angle irons 9 and 80 15 form out and in-turned guard flanges to prevent splashing of water and the escape of material from the partly open ends of the housing 14. Any suitable means for rotating the drum may be provided, and as they 85 are immaterial to the invention they have not been illustrated. For the same reason, the balls or similar grinding elements have not been shown.

The mill is strong and durable, simple in 90 construction, and highly efficient in operation.

We claim:

1. In a ball-mill, a drum, perforated liner plates in the drum, said drum having a side 100 outlet extending completely around the same and spanned by the liner plates, and a housing enclosing the drum at the site of the outlet and having a discharge opening.

2. In a ball-mill, a drum comprising end 105 sections and liner plates connecting the same in longitudinally spaced relation, the plates spanning the space between the end sections and having perforations, said space being the drum outlet, and a housing enclosing the 110 drum at the outlet and having a discharge opening.

3. In a ball-mill, a drum comprising end sections and liner plates connecting the same in longitudinally spaced relation on the inside thereof, said plates spanning the space between the end sections and having perforations, cylindrical plates connected to the outside of the end sections and extending inwardly therefrom, said cylindrical plates being spaced from each other at their inner ends, and a housing enclosing the drum at the site of the space between the inner ends of the cylindrical plates, and having an outlet.
4. In a ball-mill, a drum comprising end sections and liner plates connecting the same in longitudinally spaced relation on the inside thereof, said plates spanning the space between the end sections and having perforations, cylindrical plates connected to the outside of the end sections and extending inwardly therefrom, said cylindrical plates being spaced from each other at their inner ends, and a housing enclosing the drum at the site of the space between the inner ends of the cylindrical plates, said plates having out-turned guard flanges, and the ends of the housing having inturned flanges.
5. A ball-mill drum having a side outlet extending completely around the same, and perforated liner plates spanning said outlet.
6. A ball-mill drum comprising end sec-

tions and liner plates connecting the same in longitudinally spaced relation, the plates spanning the space between the end sections and having perforations, and said space being the drum outlet.

7. A ball-mill drum comprising end sections and liner plates connecting the same in longitudinally spaced relation on the inside thereof, said plates spanning the space between the end sections and having perforations, and cylindrical plates connected to the outside of the end sections and extending inwardly therefrom, said cylindrical plates being spaced from each other at their inner ends.

8. A ball-mill drum comprising end sections and liner plates connecting the same in longitudinally spaced relation on the inside thereof, said plates spanning the space between the end sections and having perforations, and cylindrical plates connected to the outside of the end sections and extending inwardly therefrom, said cylindrical plates being spaced from each other at their inner ends and having out-turned guard flanges thereat.

In testimony whereof we affix our signatures.

LEWIS L. SWEET.
MIKE MORLEY.
